DESIGN FOR A CASING FOR A BLOWER FOR DEFROSTING WINDSHIELDS

Albert G. Redmond, Flint, Mich.

Application May 10, 1938, Serial No. 77,099

Term of patent 14 years

To all whom it may concern:

Be it known that I, Albert G. Redmond, a citizen of the United States, residing at Flint, in the county of Genesee and State of Michigan, have invented a new, original, and ornamental Design for a Casing for a Blower for Defrosting Windshields, of which the following is a specification, reference being had to the accompanying drawing forming part thereof.

In the accompanying drawing the figure is a

perspective view of a casing for a blower for defrosting windshields showing my new design.

The other side of the casing is substantially plain and the other end thereof is like the end shown.

I claim:

The ornamental design for a casing for a blower for defrosting windshields, as shown and described.

ALBERT G. REDMOND.
